UNITED STATES PATENT OFFICE

2,523,355

AUTOMATIC HEAT CONTROL SPRINKLER
HEAD

Glen H. Cameron, Mattoon, Ill.

Application October 3, 1947, Serial No. 777,697

5 Claims. (Cl. 169—37)

1

This invention appertains to novel and useful improvements in devices utilized in conjunction with sprinkler systems.

An object of this invention is to release a valve at a predetermined temperature.

Another purpose of this invention is to provide means for releasing a pair of valve plates which are normally positioned over an intake line associated with a water supply system.

Another purpose of this invention is to provide a pair of arms connected together by means of fusible material, resiliently biased means for retaining the valve in the closed position, said resilient means urging the said means against the said arms, whereby, upon fracturing the fusible material bond as influenced by thermal conditions, a liquid will be emitted.

Another purpose of this invention is to provide antivibration means in connection with the valve closure retaining means.

Another object of this invention is to provide an extremely simple, efficient device of the nature to be described which lends itself well to commercial manufacture.

Ancillary objects and features of novelty will become apparent to those skilled in the art, in following the description of the preferred form of the present invention, illustrated in the accompanying drawings, wherein:

Figure 1 is an elevational side view of the preferred form of the present invention;

Figure 2 is an elevational view of the invention shown in Figure 1, portions being broken away in section to illustrate details of construction and showing the device in the second position of operation;

Figure 3 is a plan view of the invention shown in Figure 1;

Figure 4 is a perspective exploded view of the valve plates utilized in conjunction with and forming a part of the present invention.

Referring now in detail to the illustrated preferred embodiment of the present invention, like reference characters are used throughout to indicate similar elements thereof.

This invention has been conceived and developed to provide a device for improved functioning and actuation of sprinkler systems utilized commercially throughout building structures and the like. In order to obviate the use of but a single strand or bead of fusible material as a closure bond, the present invention has been developed which provides an increased surface area for use in retaining a fusible material, thermally responsive at a predetermined temperature.

2

A bonnet 10 is provided with an externally threaded inlet 12 which is adapted to be secured to a suitable liquid supply, such as a water main or the like. This bonnet 10 also has a partition 14 extending thereacross with an aperture 16 at substantially the longitudinal center thereof.

A pair of valve plates or disks 18 and 20, respectively, are provided, the said disk 18 being adapted to seat in the aperture or bore of the said inlet means 12. Of course, a reduced portion may be provided in association therewith for firm seating within the said bore. The said valve plate 20 also has a reduced portion at the upper extremity or surface thereof with an aperture 22 therein for a purpose to be described hereinafter.

A pair of bosses 24 and 26, respectively, are provided integral with the said bonnet 10, while pivot pins 28 and 30 extend therethrough. A pair of arms 32 and 34, respectively, are secured to each pivot pin and extension plates 36 and 38, respectively, extend at right angular relation relative to each arm 32 and 34. These plates are secured in fixed position through the utility of a conventional fusible material.

A rod generally indicated at 40 is provided through a suitable aperture 42 in the upper portion of the said bonnet 10 and proceeds through the said aperture 16 in the partition 14. This rod is preferably composed of a sleeve 44 having a slot 46 at the upper portion thereof. The said sleeve is also preferably internally threaded for the purpose of receiving an arm 48 in adjustable position in the said bore thereof. Of course, a suitable nut 50 and washer 52 may be utilized in association with securing the said arm 48 in the selected adjusted position relative to the sleeve 44.

Means for resiliently biasing the arm 48 relative to the valve plate is provided. This means is preferably a spring 52 seated on a suitable washer 54 which is positioned on the partition 14 and a second washer 56 engageable with the lower surface of the said nut 50. It is quite obvious that by utility of this expedient the slot 46 is constantly urged against a selected extension plate 36, against the bond of the said fusible material.

It will be noted from an inspection of Figure 2 that the lower extremity of the arm 48 is preferably conical, engaging the aperture 22 of the upper valve plate 20.

The operation of the present invention is deemed obvious from the foregoing. At a predetermined temperature, the bond holding the

plate extensions 36 and 38 together is broken, thereby permitting the resilient means 52 to urge the rod 48 in out-of-contact relation with the valve plates. The water pressure in the system will also urge the plates from their seats, thereby effecting sprinkling. The slot 46 engageable with the plate extension 36 effects an anti-twist and anti-vibration means and also assists in the operation and actuation of the invention.

It is apparent that variations may be made herein without departing from the spirit of the invention. Accordingly, limitation is sought only in accordance with the scope of the following claims.

Having described the invention, what is claimed as new is:

1. A sprinkler apparatus comprising a bonnet having a platform therein, an inlet engageable with a liquid source of supply, detachable valve means associated with said inlet, means extending through said platform for actuating said valve means at a predetermined temperature, said valve actuation means including a sleeve associated with said bonnet, a groove in said sleeve and a shank adjustably secured to said sleeve, arms pivoted to said bonnet, one of which is engageable in said slot, fusible means for retaining said arms in a predetermined position, means seated on said platform for resiliently biasing said sleeve, and said shank engaging said detachable valve means.

2. In a sprinkler apparatus, a bonnet, an inlet in said bonnet adapted to be secured to a liquid supply line, valve plates associated with said inlet, thermal responsive means for actuating said valve means, said actuation means including a sleeve and an aperture in said sleeve, a rod in said aperture, arms pivoted to said bonnet, fusible means for retaining said arms in engagement with said rod and resilient means for retaining said rod in engagement with said valve plates, means for preventing rotation of said rod relative to said bonnet, and said resilient retaining means comprising a spring.

3. In a sprinkler apparatus, a bonnet, an inlet in said bonnet adapted to be secured to a liquid supply line, valve plates associated with said

inlet, thermal responsive means for actuating said valve means, said actuation means including a sleeve and an aperture in said sleeve, a rod in said aperture, arms pivoted to said bonnet, fusible means for retaining said arms in engagement with said rod and resilient means for retaining said rod in engagement with said valve plates, means for preventing rotation of said rod relative to said bonnet, said resilient retaining means comprising a spring, and said rotation preventing means including a slot in said rod engaging a selected arm.

4. In a sprinkler apparatus, a bonnet having a liquid inlet, a valve member disposed in the inlet closing position, a rod slidably carried by said bonnet and in separable engagement with said valve member, a spring reacting on said bonnet and said rod constantly urging said rod away from said member, and fusible means carried by said bonnet for retaining said rod against said valve member against the biasing force of said spring including a pair of arms pivoted to said bonnet and connected together by a fusible material.

5. In a sprinkler apparatus, a bonnet having a liquid inlet, a valve member disposed in the inlet closing position, a rod slidably carried by said bonnet and in engagement with said valve member, a spring reacting on said bonnet and said rod constantly urging said rod away from said member, and fusible means carried by said bonnet for retaining said rod against said valve member against the biasing force of said spring, a slot in said member, and at least one of said arms disposed in said slot to prevent rotation of said member.
